UNITED STATES PATENT OFFICE.

LEE T. ALTON, OF BROOKLYN, NEW YORK.

DESIGN FOR A TUBE FOR INCANDESCENT GAS-BURNERS.

SPECIFICATION forming part of Design No. 28,184, dated January 18, 1898.

Application filed December 10, 1897. Serial No. 661,458. Term of patent 14 years.

To all whom it may concern:

Be it known that I, LEE T. ALTON, a citizen of the United States, residing at Brooklyn, county of Kings, and State of New York, 5 have invented and produced a new and original Design for a Tube for Incandescent Gas-Burners, of which the following is a specification.

My invention relates to a design for a tube for incandescent gas-burners; and it consists in the configuration of the same, substantially as herein shown and described.

In the drawings forming part of this specification, Figure 1 is a front elevation of the 5 tube; and Fig. 2, a sectional elevation substantially on the plane of the line 2, Fig. 1.

At 1 in the drawings is a conical tube presenting the figure of an inverted truncated cone by reason of its greatest diameter being 10 superposed, as at 2, its diverging walls 3 germinating at the base 4 of smallest diameter.

At 5 is a dome-shaped tube comprising a dome-shaped lower tube 6, having an interior thread 7 spirally disposed at the lower opening of said latter tube and elliptical open-

ings 8 formed in its shell, and a superposed tubular nipple 9, cylindrical exteriorly and interiorly coned, as at 10, the union of the tubes 6 and 9 forming a dome, as at 11, the conical base 4 of the tube 1 fitting into the 30 conical interior of the nipple 9.

At 12 is a cylindrical collar fitting about the tube 6, provided with elliptical openings 13 and a horizontally-disposed slot 14, a circular stud 15 extending outwardly from the tube 6, 35 through the slot 14, which is provided with a circular head 16 exterior to the collar 12.

The tube 1 is provided adjacent the top 2 with a circumferential flange 17.

Having described my invention, I claim— 40

The design for a tube for incandescent gas-burners, substantially as herein shown and described.

Signed at the city, county, and State of New York this 3d day of December, 1897.

LEE T. ALTON.
